STEREO SYSTEM CONTROL PANEL

Arthur Robson, Jericho, N.Y., assignor to
Morse Electro Products Corp., Brooklyn, N.Y.

Filed Jan. 12, 1972, Ser. No. 217,433

Term of patent 14 years

Int. Cl. D13—03

U.S. Cl. D26—13 C

FIG. 1

FIG. 2

FIG. 3

FIG. 4

FIG. 5

FIG. 1 is a front perspective view showing a first embodiment of a stereo system control panel according to the present invention;

FIG. 2 is a top plan view of the embodiment of FIG. 1 and a top plan view of an alternative embodiment shown in front elevational view in FIG. 5;

FIG. 3 is a front elevational view of the embodiment of FIG. 1;

FIG. 4 is a side elevational view of the embodiments of FIGS. 1 and 5 taken from the right side, the left side view not being shown since it is identical to the right side view; and

FIG. 5 is a front elevational view of an alternative embodiment according to the present invention.

I claim:

The ornamental design for a stereo system control panel, as shown and described.
